[57] ABSTRACT

An input diplexer separates wide frequency range signals by frequency to provide, at a plurality of outputs, signals within different narrow frequency bands. A plurality of quadrature hybrids are adapted so that each hybrid achieves equal power division and 90° relative phase shift with low distortion over one of the narrow frequency bands. A hybrid is coupled to each output of the input diplexer. Output diplexers are coupled to the two outputs of each of the hybrids to combine the power divided narrow frequency band signals into two wide frequency band signals of substantially equal power and of 90° differential phase.

WIDEBAND HYBRID SYSTEM

BACKGROUND OF THE INVENTION

This invention relates to hybrids and more particularly to a polarizer using a system of hybrids for achieving 90° differential phase shift and power splitting over a wide band of frequencies with low amplitude and phase error.

It is desirable for achieving circular polarization that the signals fed to the orthogonally polarized antenna radiating element be at phase quadrature or 90° difference in relative phase and that the power be exactly divided. A practical way of achieving this with low loss is by means of a short slot hybrid. Although these short hybrid slot devices have had humps put at the center of the short slot region or the cross sectional width made smaller near the slotted region to achieve broadband operation, these hybrid structures remain relatively narrow band devices. When one of these devices is operated over a wide frequency band such as for example from 3,700 to 4,200 MHz (as in satellite communication systems), phase error of over 5° is produced at some frequencies in the band. Consequently, relatively high axial ratios occur when the outputs of one of these are applied to the elements of an antenna. Wideband polarizers capable of achieving axial ratios in the order of 0.25 to 0.5 db are required over these above frequencies in satellite communication systems. This has heretofore not been achieved over such widebands using hybrids.

Briefly, according to the present invention substantially lower amplitude and phase error is achieved for providing equal power division and 90° relative phase shift between the power divided outputs by the use of a first diplexer for subdividing the signals by frequency into subfrequency bands and by coupling the narrow frequency band signals to separate hybrids. The separate hybrids are each adapted to provide at their two separate outputs, power division and 90° relative phase shift between the power divided signals over the particular narrow frequency band coupled thereto with minimum amplitude and phase error. That one of the two outputs from each of the separate hybrids having substantially identical phase is coupled to a second diplexer for combining the narrow band signals to a first wideband output. The second output from each of the separate hybrids is coupled to a third diplexer for combining the 90° relative phase shifted narrow frequency band signals to a second wideband output.

A more complete description of the subject invention follows in conjunction with the following drawings wherein:

FIG. 1 is a schematic diagram of a wideband hybrid system and a polarizer system using the same according to the present invention.

FIG. 2 is a perspective view of a portion of a wideband hybrid system shown in FIG. 1 with a portion of the top walls removed.

Referring to the block diagram of FIG. 1, there is shown a wideband hybrid system 10 consisting of two dippers 11 and 11a at the input and two output dippers 41 and 43 with four short slot quadrature hybrids 21, 23, 25 and 27 coupled therebetween. The purpose of the circuit is to divide the input power fed to the input terminal I₁ of diplexer 11 into two parts occurring at the output terminals O₁ of diplexer 41 and O₂ of diplexer 43 in such a way that the output powers are

equal in amplitude, 90° different in relative phase and no output power is coupled at I₂ or reflected back to I₁. Further, the purpose of the circuit is that the terminal I₁ of diplexer 11 and the I₂ terminal of diplexer 11a be interchangeable and simultaneously useful. All of the above functions are maintained in the f₁ through f₅ frequency band. Circular polarization is achieved by coupling the output at terminal O₁ to one terminal 9a of an orthogonal coupler 9, for example, and the other output at terminal O₂ is coupled to an orthogonally oriented terminal 9b of coupler 9. If these outputs at O₁ and O₂ are equal in power and at phase quadrature pure circular polarization is achieved. The coupling to the orthogonally oriented terminal 9b may require a rotation of the polarization attitude 90°. This rotation may be accomplished by a twisted waveguide section (rotator) 8 located in the coupling lead between terminal O₂ and terminal 9b.

The input signal I₁ at frequencies f₁ to f₅ is divided on the basis of frequency by diplexer 11 into four frequency bands f₁ to f₂; f₂ to f₃; f₃ to f₄ and f₄ to f₅. The diplexer 11 is made up of a power divider 13 followed by a plurality of band-pass filters 15, 16, 17 and 18. The power divider 13 splits the input signal power into, for example, four signals of equal power and couples these separate signals to separate filters 15, 16, 17 and 18. The band-pass filter 15 is selected to pass those frequencies within the f₁ to f₂ frequency band. Similarly, band-pass filters 16, 17 and 18 are selected to pass the frequency bands f₂ to f₃; f₃ to f₄ and f₄ to f₅ respectively.

A plurality of hybrids 21, 23, 25 and 27 equal to the number of band-pass filters is provided. The hybrid 21 is adapted to provide equal power division of the input signal with 90° differential phase shift between the power divided signals. The hybrid 21 is designed to accomplish this with minimum phase and amplitude error between its two output ports over the frequencies of from f₁ to f₂. The output of band-pass filter 15 is coupled via lead 29 to input terminal 21a of hybrid 21. The hybrid 23 is similarly adapted to operate as a 90° differential phase shifting power dividing coupler but with minimum phase and amplitude error over the frequencies from f₂ to f₃. The output of band-pass filter 16 is coupled via lead 30 to terminal 23a of hybrid 23. The hybrid 25 is similarly a 90° differential phase shifting power dividing coupler which is adapted to operate with minimum phase and amplitude error over the frequencies from f₃ to f₄. The output of band-pass filter 17 is coupled via lead 31 to terminal 25a of hybrid 25. The hybrid 27 is a 90° differential phase shifting power dividing coupler which is adapted to operate with minimum phase and amplitude error over the frequencies from f₄ to f₅. The output of band-pass filter 18 is coupled via lead 32 to terminal 27a of hybrid 27. The hybrids 21, 23, 25 and 27 may each be short slot hybrids as described, for example, by Riblett in U.S. Pat. Nos. 2,739,287 and 2,739,288. Basically, each of these short slot hybrids consists of two rectangular waveguide sections having a common wall with an aperture in the common wall. Signals coupled to one of the waveguides are power divided at the aperture with one half of the power coupled through the aperture and phase shifted 90° relative to the other one half of the signal which is coupled to the other end of the input waveguide without such additional phase shift.

The output from the quadrature hybrids 21, 23, 25 and 27 are coupled to dippers 41 and 43. The di-

plexer 41 includes band-pass filters 45, 46, 47 and 48. Band-pass filter 45 is adapted to couple only those signals with low attenuation between the frequencies of f_1 to f_2 . Similarly, band-pass filter 46 is adapted to pass the frequencies of f_2 to f_3 . Band-pass filter 47 is adapted to pass the frequencies between f_3 to f_4 with low attenuation and band-pass filter 48 is adapted to pass frequencies between f_4 to f_5 with low attenuation. In the diplexer 41 the outputs of band-pass filters 45, 46, 47 and 48 are each coupled to a power combiner 49 wherein the signals at frequencies from f_1 to f_5 are combined to provide an output at terminal O_1 . Diplexer 43 is similarly arranged comprising band-pass filter 55 covering the frequency range from f_1 to f_2 , band-pass filter 56 covering the frequency range from f_2 to f_3 , band-pass filter 57 covering the frequency range from f_3 to f_4 and band-pass filter 58 covering the frequency range from f_4 to f_5 . All the output power at the band-pass filters 55 through 58 are combined at power combiner 59 to provide a single output at output terminal O_2 of diplexer 43.

The power divided signal at terminal 21b of hybrid 21 is coupled via lead 33 to band-pass filter 45 in diplexer 41. The equal power 90° phase shifted signal at terminal 21c of hybrid 21 is coupled via lead 35 to band-pass filter 55 of diplexer 43. The one half power output signal at terminal 23b of hybrid 23 is coupled via lead 37 to band-pass filter 46 of diplexer 41. The equal power 90° relative phase shifted signal from hybrid 23 at terminal 23c is coupled via lead 38 to band-pass filter 56 of diplexer 43. The half power output signal from hybrid 25 at terminal 25b is coupled via lead 39 to band-pass filter 47 of diplexer 41. The equal power and 90° relative phase shifted signal at terminal 25c of hybrid 25 is coupled via lead 40 to band-pass filter 57 of diplexer 43. The half power output signal at terminal 27b of hybrid 27 is coupled to band-pass filter 48 of diplexer 41 via lead 36. The equal power 90° differential phase shifted signal at terminal 27c is coupled via lead 34 to band-pass filter 58 of diplexer 43.

In the operation of the device described in FIG. 1, the input signals I_1 of frequencies from f_1 to f_5 which cover the operating frequency band of the system are coupled to the input power divider 13 wherein these signals are divided into four equal power sections and coupled to the respective filters 15, 16, 17 and 18. The filter 15 passes frequencies from f_1 to f_2 to short slot hybrid 21. At the hybrid 21 the f_1 to f_2 frequency signals are equally power divided and with one portion undergoing zero or reference phase shift to terminal 21b and the other portion undergoing 90° differential phase through the short slot 22 in hybrid 21 to terminal 21c. The output at terminal 21b is coupled to band-pass filter 45 in diplexer 41 via lead 33. The 90° differential phase shifted signal at terminal 21c is coupled via lead 35 to band-pass filter 55 of diplexer 43. Similarly, those signals at frequencies from f_2 to f_3 are coupled to short slot hybrid 23 and power divided such that those signals at the reference phase at hybrid terminal 23b are coupled to band-pass filter 46 of diplexer 41 and the 90° differential phase shifted signals at terminal 23c are coupled to band-pass filter 56 of diplexer 43. Those signals between frequencies f_3 to f_4 are coupled to short slot hybrid 25 with the one half power output at terminal 25b at reference phase coupled to band-pass filter 47 of diplexer 41 and those half power signals undergoing 90° differential phase shift being coupled out of ter-

5 minal 25c to band-pass filter 57 of diplexer 43. The signals at frequencies between f_4 and f_5 are coupled out of band-pass filter 18 to short slot hybrid 27. The output signals at reference phase at terminal 27b of hybrid 27 are coupled to band-pass filter 48 of diplexer 41 and the 90° differential phase shifted signals at terminal 27c are coupled to band-pass filter 58 of diplexer 43. As can be seen by reviewing the above, those signals which undergo the 90° additional phase shift are coupled to 10 the diplexer 43 and the other signals of equal power but of reference phase are coupled to diplexer 41. The signals at the band-pass filters 45 through 48 are combined at power combiner 49 to provide one half the total output power at the reference phase at terminal 15 O_1 . The band-pass filters 55 through 58 are coupled to power combiner 59 wherein the other half of the total power at the frequencies from f_1 to f_5 are combined and applied to the output terminal O_2 . The power at terminal O_2 should approximately equal the power at terminal O_1 , and be at 90° relative phase to the phase of the signal at terminal O_1 .

20 A nearly circular polarized wave with a relatively low axial ratio of powers at the two terminals is achieved for example by coupling the output at terminal O_1 to one terminal 9a of orthogonal coupler 9 and by coupling the other output at terminal O_2 to terminal 9b of the orthogonal coupler 9 via attitude rotator 8. The orthogonal coupler 9 may be coupled at terminal 9c to a radiating horn antenna, not shown, whereby the circular polarized waves are radiated or received. The orthogonal coupler 9 may be a square section of waveguide (not shown) with the terminals 9a and 9b oriented to excite the output signal at terminal O_1 in for example a TE_{10} mode and to excite the output signal at terminal O_2 in the orthogonal TE_{01} mode. Metal irises (not shown) can be placed across the input of terminal 9a orthogonal to the electric field in the TE_{10} to provide isolation of the two terminals 9a and 9b. A typical waveguide orthogonal coupler may be like that shown 30 in FIG. 8 and described in connection therewith in U. S. Pat. No. 3,569,870 issued to Peter Foldes.

40 Input signals applied to terminal I_2 in FIG. 1 undergo similar operation to that described above for input signals applied to diplexer 11. Input signals applied to terminal I_2 of diplexer 11a are power divided at divider 13a with those signals from frequency f_1 to f_2 being coupled through filter 15a and lead 29a to terminal 21d of hybrid 21. Similarly, those signals at frequencies f_2 to f_3 at divider 13a are coupled through filter 16a and lead 30a to terminal 23d of hybrid 23. Signals at frequencies f_3 to f_4 at divider 13a are passed through filter 17a and lead 31a to terminal 25d of hybrid 25. Signals at frequencies f_4 to f_5 at divider 13a are passed through filter 18a and lead 32 to terminal 27d of hybrid 27. The operation of the hybrids 21, 23, 25 and 27 and dippers 41 and 43 is similar to that described above with the output at terminals O_2 and O_1 being of equal power at 90° relative phase but in this case the output at terminal O_1 undergoes the additional 90° phase shift and the output at terminal O_2 is at reference phase. This is due to the fact that the signals which are ultimately coupled to diplexer 41 are coupled through the slots in each of the hybrids 21, 23, 25 and 27.

55 60 65 As mentioned previously, it is desirable that the device be reciprocal. It can be seen that by making the power dividers and power combiners identical by having them both with the filters at the input and output

terminals of the hybrids, reciprocal operation is provided. For example, signals applied at output terminal O_1 of diplexer 41 can also undergo the frequency division of the signals corresponding to f_1 to f_2 , f_2 to f_3 , f_3 to f_4 and f_4 to f_5 and be applied to the corresponding hybrids 21, 23, 25 and 27. Since the hybrids are symmetrical, the two output signals from each of the hybrids are of equal power with 90° relative phase shift between the two output signals. Diplexer 11 in the example combines the signals of reference phase and the diplexer 11a combines the signals having the additional 90° phase shift. Also, it is necessary that these hybrids 21, 23, 25 and 27 at either end see a similar match. This is provided by having similar band-pass filter sections coupled at each terminal of a given hybrid.

Turning to FIG. 2, there is illustrated the construction of a portion of such a wideband hybrid system. Only two diplexer sections and the multiple hybrid section is illustrated in the assembly 61 shown since the remaining two diplexer sections (not shown) of the assembly 61 are identical in construction to the first two dippers. Waveguide assembly 61 as shown in FIG. 2 is made up of two waveguide sections 63 and 64 each sharing a common narrow wall 65. The waveguide section 63 further includes broad walls 67 and 69 and narrow wall 70 opposite common wall 65. The waveguide section 64 includes opposite broad walls 71 and 73 and narrow wall 75 opposite common wall 65. The top walls 67 and 71 are formed by one continuous conductive plate and the bottom walls 69 and 73 are formed by one continuous conductive plate. The waveguide section 63 is power divided into four equal rectangular waveguide sections by three plates 77, 78 and 79, which are placed parallel to each other and parallel to walls 69 and 67. Similarly, plates 81, 82 and 83 are placed within waveguide section 64. The input signal applied to waveguide 63 is then power divided by a factor of four into separate waveguide sub-sections formed between the plates 77, 78 and 79 and between plate 77 and wall 67 and between plate 79 and wall 69.

The input signals coupled to the input of waveguide section 64 are power divided between the plates 81, 82 and 83 and between the plate 81 and wall 73 and between broad wall 71 and plate 83. By placing tuning stubs or irises 91 in the sub-sections between the plates and the broad walls, the waveguide sub-sections formed between the plates and between the plates and the broad walls of the waveguide can be made to pass different frequencies and thusly provide frequency separation. In the arrangement shown in FIG. 2, the irises 91 are placed within these sections to form band-pass filters for passing, for example, at the top waveguide sub-section 63a formed between wall 67 and plate 77, a band-pass filter at f_1 to f_2 frequencies. Similarly, the sub-section 63b formed between the plates 77 and 78 passes frequencies from f_2 to f_3 , the sub-section 63c between plates 78 and 79 passes frequencies from f_3 to f_4 and the sub-section 63d formed between plate 79 and wall 69 passes frequencies from f_4 to f_5 . Similarly, the band-pass filters at frequencies f_1 to f_2 , f_2 to f_3 , f_3 to f_4 and f_4 to f_5 are provided by the waveguide sub-sections 64a, 64b, 64c and 64d having appropriately placed irises 91 therein. Hybrids 92, 93, 94 and 95 are provided by apertures 92a, 93a, 94a, and 95a in the common wall 65 between waveguide sub-sections 63a and 64a, 63b and 64b, 63c and 64c and 63d and 64d and by joining plate 77 to 83, plate 78 to 82, and plate 79 to

81 at these apertures. At the hybrids 92, 93, 94 and 95 the signals are power divided with the outputs from the two output terminals of each hybrid being substantially 90° out of phase and of substantially equal power. The 5 outputs from the hybrids 92, 93, 94 and 95 are coupled to a structure (partly shown) which is a continuation of waveguide sections 63 and 64. The remaining structure is similar to that shown at the input but is symmetrically arranged so that the outputs of the hybrids are coupled to the band-pass filter sections including the plates and irises and the output of the filter sections is coupled to the undivided waveguide section to form a combiner. The filter section coupled to each terminal of each hybrid is made substantially the same.

10 Numerous and varied other arrangements within the sphere and scope of the principle of the invention will have occurred to those skilled in the art. The general principles of the invention are, for example, readily applicable to systems employing two or more hybrids and corresponding band-pass filters and power dividers. Power division can be up to any n number of sections with n band-pass filters and n hybrids to achieve the desired minimum phase and amplitude error through such hybrids. In the configuration using only two such hybrids, four dippers and an orthogonal coupler, an axial ratio on the order of 0.35 db is achieved in the 15 3,700 to 4,200 MHz frequency band.

What is claimed is:

1. A system for providing substantially equal power splitting and 90° relative phase shift of power divided signals over a given relatively wide band of frequencies with reduced amplitude and phase error comprising:
  - a. first diplexer responsive to signals of said given wide band of frequencies at its input for separating said signals by frequency to provide at a plurality of first diplexer output terminals signals within different narrow frequency bands where the sum of said narrow frequency bands covers the frequency spectrum of said given wide band of frequencies, a plurality of quadrature hybrids, each hybrid coupled to a different one of said plurality of first diplexer output terminals and adapted to provide equal power splitting to first and second hybrid output terminals with signals at the first hybrid output terminal undergoing 90° less phase shift than the signals at the second hybrid output terminal with minimum error over the coupled relatively narrow frequency band,
  - b. a second diplexer coupled to said first hybrid output terminal of each of said plurality of hybrids and being responsive to said signals within each of said narrow frequency bands for providing at the second diplexer output terminal wide frequency band signals of a given power level and phase,
  - c. a third diplexer coupled to the second hybrid output terminal of each of said plurality of hybrids and being responsive to said signals within each of said narrow frequency bands for providing at the third diplexer output terminal said wide frequency band signals of a power level substantially equal to said given power level and at 90° relative phase to said given phase,
2. A wideband polarizer for providing circularly polarized waves from linearly polarized waves over a given wide band of frequencies with low axial ratio comprising:

a first diplexer responsive to the linearly polarized signals over the given wide band of frequencies at its input for separating said linearly polarized signals by frequency to provide at a plurality of first diplexer output terminals linearly polarized signals within different narrow frequency bands where the sum of said narrow frequency bands covers the frequency spectrum of said given wide band of frequencies,

a plurality of quadrature hybrids, each hybrid coupled to a different one of said plurality of first diplexer output terminals and adapted to provide equal power splitting to first and second output hybrid terminals with linearly polarized signals at the first hybrid output terminal undergoing 90° less phase shift than the linearly polarized signals at the second hybrid output terminal with minimum error over the coupled relatively narrow frequency band, a second diplexer coupled to said first hybrid output terminal of each of said plurality of hybrids and being responsive to said linearly polarized signals within each of said narrow frequency bands for providing at the second diplexer output terminal wide frequency band linearly polarized signals of a given power level and phase,

a third diplexer coupled to the second hybrid output terminal of each of said plurality of hybrids and being responsive to said linearly polarized signals within each of said narrow frequency bands coupled thereto for providing at the third diplexer output terminal said wide frequency band linearly polarized signals of a power level substantially equal to said given power level and at 90° relative phase to said given phase,

an orthogonal coupler having a first terminal coupled to the second diplexer output terminal and an orthogonally oriented second terminal coupled to the third diplexer output terminal and responsive to linearly polarized signals for providing circularly polarized waves over said wide band of frequencies with substantially low axial ratio.

3. The combination claimed in claim 2, wherein said first, second and third dipoles include band-pass filters coupled to the terminals of said hybrids.

4. The combination claimed in claim 3 wherein all of the band-pass filters coupled to a given one of said hybrids are substantially identical.

5. The combination claimed in claim 2, wherein said hybrids are short slot hybrids.
